PAINT BRUSHES

Robert L. Weiss and Earl R. Hunt, Wooster, Ohio, assignors to The Wooster Brush Company, Wooster, Ohio, a corporation of Ohio

Filed Feb. 1, 1962, Ser. No. 170,344

4 Claims. (Cl. 15—192)

This invention relates to paint brushes and like structures and more particularly to attachment means for securing the bristle portion of a brush to the handle portion thereof.

The invention has for its primary object the provision of a device of the aforesaid nature which is characterized by its structural simplicity, its inexpensive manufacturing and operating costs, the ease of assembly of its parts, the attractive forms in which the device may be made, and the particularly effective manner in which it performs its function.

An important object of the invention is to provide a paint brush structure wherein the handle portion has a peripheral wall and means is provided for both bonding a bristle portion to said wall and mechanically interlocking said bristle portion therewith.

Another object of the invention is to provide a structure as set forth above wherein a solidified bonding compound used for bonding and mechanically interlocking the bristle portion with the handle portion of a brush also serves as a lateral reinforcement preventing collapse of the side walls of a hollow plastic handle.

Further objects of the present invention, and a number of its advantages, will be referred to in or will be evident from the following description of four embodiments of the invention, illustrated in the accompanying drawings, in which:

FIG. 1 is a front elevation of a paint brush manufactured according to a first embodiment of this invention;

FIG. 2 is a side elevation of the brush of FIG. 1;

FIG. 3 is a vertical section taken along the line 3—3 of FIG. 2;

FIG. 4 is a vertical section taken along the line 4—4 of FIG. 1;

FIG. 5 is a section similar to FIG. 4 showing the second embodiment of the invention;

FIG. 6 is a view similar to FIGS. 4 and 5 showing a third embodiment of the invention;

FIG. 7 is a front elevation of a brush manufactured according to a fourth embodiment of the invention;

FIG. 8 is a side elevation of the paint brush as shown in FIG. 7;

FIG. 9 is a vertical section taken along the line 9—9 of FIG. 8;

FIG. 10 is a vertical section taken along the line 10—10 of FIG. 7; and

FIG. 11 is a horizontal cross section taken along the line 11—11 of FIG. 9.

Before the device here illustrated is specifically described, it is to be understood that the invention here involved is not limited to the structural details or arrangement of parts here shown since paint brushes embodying the present invention may take various forms. It is also to be understood that the phraseology or terminology herein employed is for the purpose of description and not of limitation since the scope of the present invention is denoted by the appended claims.

Referring now to the drawings in all of which like parts are designated by like reference numerals, the paint brush of FIGS. 1—4 comprises a handle 1, a bristle portion 2, and a ferrule 3. The handle 1, as herein illustrated, is preferably made of plastic and comprises a gripping portion 4 and an integral, bristle receiving portion 5. The entire handle is preferably of hollow construction thereby great-

2

ly reducing the weight of said handle and effecting a substantial saving in material. The bristle receiving portion 5 is generally oblong in horizontal section with the shape of said portion being defined by a relatively thin, vertical peripheral wall 6 having flat, elongated parallel side portions 7 and shorter end portions.

The outer surface of the vertical, peripheral wall 6 is inwardly stepped adjacent its upper end to provide a downwardly facing shoulder 8. The side portions 7 of the wall have downwardly directed extensions 9 integral with said side portions and disposed opposite each other. The side portions 7, in the form illustrated, are also connected to each other by integrally formed webs 10 of substantial thickness which provide lateral reinforcement of the side portions 7.

As best shown in FIG. 4, the lowermost ends of the extensions 9 have inwardly directed flanges 11 which extend throughout the horizontal length of said extensions and for more than half the length of the elongated parallel side portions 7. The outer surfaces of the extensions 9 are coplanar with the outer surfaces of their associated side portions 7, and the preferably metal ferrule 3 surrounds the wall 6 in flatwise engagement with its outer surface and the outer surfaces of said extensions, said ferrule having its upper peripheral edge seated against the shoulder 8. Said ferrule extends downwardly a substantial distance below the inwardly turned flanges 11 and is preferably provided with one or more reinforcing beads or ribs 12 extending horizontally completely around said ferrule.

The bristle portion 2 comprises a multiplicity of closely packed bristles 20 divided within the bristle portion into three substantially equally proportioned rows by means of a pair of separation strips 21. The separation strips 21 may be made of wood, metal, plastic, or other suitable materials and are disposed with their top surfaces coplanar with the upper ends of the bristles 20. The upper ends of said bristles and the separation strips are unitarily bonded together to form the bristle knot and are disposed within the lower end portion of the ferrule 3.

One method of manufacturing the brush is by first disposing the upper ends of the bristles 20 within the lower end portion of the ferrule 3 with the separation strips 21 disposed as illustrated in FIG. 4. A bonding compound 22 in liquid form is then poured into the ferrule 3 in such quantity as to rise a substantial distance within said ferrule. Some of the liquid compound permeates the upper ends of the bristles 20 whereby when said compound hardens, the upper ends of the bristles are bonded together into a solid bristle knot. The handle 1 is inserted into the upper end of the ferrule 3 while the compound 22 is still in a liquid state, and the flanges 11 are then disposed below the upper level of the compound which is subsequently cured into a hardened state.

The bonding compound 22 is preferably a thermosetting material such as an epoxide containing composition which subsequently hardens with the flanges 11 embedded therein whereby the bristle knot is not only bonded to the lower edge portions of the extensions 9 and the inner surface of the ferrule 3, but also mechanically interlocks with said flanges of said extension. The hardened bonding compound 22 also affords a rigid, lateral connection and reinforcement between the extensions 9 thereby adding substantially to the rigidity and strength of the bristle receiving portion 5 of the handle 1.

The second embodiment of FIG. 5 differs from the first embodiment only in the transverse sectional shape of the downwardly directed extensions. All other parts are identical with those of the first embodiment and are, therefore, given the same reference numerals. The embodiment of FIG. 5 has extensions 14 which turn inwardly in a downward direction and have inwardly directed flanges 15 at their lowermost edge portions. The outer

surfaces of the extensions 14 adjacent their lower edges are, therefore, disposed in spaced relation to the inner surfaces of the ferrule 3, and the bonding compound 22 fills this space as illustrated in FIG. 5.

The third embodiment of FIG. 6 illustrates the manner in which the flanges of the extensions may be directed outwardly if desired. In the third embodiment, all parts are substantially similar to and numbered the same as corresponding parts of the first embodiment with the exception of the wall of the bristle receiving portion 5, the side portions of the wall, and the extensions of the side portions.

The wall 16 of the third embodiment is preferably somewhat thicker than the wall 5 of the first two embodiments resulting in thickened side portions 17 and downwardly directed extensions 18. The lower portions of the extensions 18 taper downwardly away from the walls of the ferrule 3 at their outer surfaces as indicated at 18', and the lower edges of said extensions have laterally outwardly directed flanges 19. By means of the tapers 18', the flanges can be directed outwardly without changing the shape of the ferrule and without distorting the extensions 18. The bonding compound 22 extends upwardly above the flanges 19 as in the first two embodiments whereby the extensions 18 are both bonded to and interlocked with the bristle portion 2.

The fourth embodiment of FIGS. 7-11 shows a paint brush of similar construction to that shown in the first embodiment although illustrated as applied to a smaller brush. The brush of the fourth embodiment comprises a handle 30, a bristle portion 31, and a ferrule 32. The handle is preferably of hollow, plastic construction so formed as to provide a gripping portion 33 and a bristle receiving portion 34.

The bristle receiving portion 34 has a downwardly projecting, peripheral wall 35 which defines an oblong shape in horizontal section and which has parallel, flat side portions 36 and preferably rounded end portions 37. The wall 35 is of uniform vertical dimension throughout and is uniformly inwardly stepped at its outer surface adjacent the upper end to afford a downwardly facing shoulder 38 against which the upper peripheral edge of the ferrule 32 seats. The wall 35 is provided, adjacent its lower peripheral edge with a plurality of apertures 39 which are preferably provided only in the side portions 36 but which may be provided also in the end portions 37.

The ferrule 32 projects downwardly a substantial distance below the lower edge of the wall 35 to provide a socket for receiving the bristle knot, said ferrule being provided with one or more reinforcing ribs 40 adjacent its lower end if desired. The bristle portion 31 of the second embodiment comprises a plurality of closely packed bristles 50 having a central divider or separation strip 51 at the upper ends of the bristles at the bristle knot.

In final assembly, the bristle knot is disposed within the downwardly opened socket formed by the lower end of the ferrule 32 with the upper end of said knot contiguous the lower peripheral edge of the wall 35. The upper ends of the bristles, the separation strip, the lower portion of the wall, and the lower portion of the ferrule are all unitarily bonded together by a bonding compound 52, of a type previously referred to, which extends upwardly into the hollow, bristle receiving portion 34 of the handle above the level of the apertures 39 whereby in its liquid state said compound flows outwardly into said apertures. Hardening or curing of the bonding compound 52 into a solid state provides a mechanical interlock between the bristle knot and the handle, by means of the portion thereof projecting into the apertures, and also adhesively bonds the two parts into a solid, integral unit.

A brush constructed according to any of the embodiments herein presented is sturdy, light in weight, and inexpensive to manufacture. It has the advantage that no nails or rivets are necessary to hold the several parts together. The handle and the ferrule are, in each instance,

effectively sealed against paint or moisture collecting therein due to the fact that the entire area of the bristle knot is sealed relative to the ferrule and/or the handle by the aforementioned bonding compound. The bristle receiving portion of the handle in each embodiment is reinforced against collapsing in a lateral direction by this same bonding compound which affords a rigid connection between the flat side portions of the walls.

It will be understood that many changes may be made in the above described invention without, however, departing from the spirit thereof or the scope of the appended claims.

What is claimed is:

1. A brush structure comprising a hollow, thin-walled handle; said handle affording downwardly projecting elongated side walls and shorter end walls, said side walls providing parallel and laterally spaced wall portions at opposite sides of said handle; the lower edges of said wall portions having laterally directed, elongated flanges extending for more than half the length of said elongated side walls; a tubular ferrule surrounding the lower portion of said handle and said wall portions and extending downwardly below the lower edges of said wall portions; a bristle portion having its upper end telescoped within the lower end of said ferrule and disposed below the lower edges of said wall portions; solidified bonding compound disposed within said ferrule, bonding the upper end of said bristle portion into a solid bristle knot, and extending upwardly within said ferrule above said flanges thereby rigidly bonding and locking said wall portions to said bristle portion.

2. A brush structure comprising a hollow, thin-walled handle; said handle affording downwardly projecting elongated side walls and shorter end walls, said side walls providing parallel and laterally spaced wall portions at opposite sides of said handle; an elongated flange formed on the inner surface of each said wall portion adjacent to the lower edge of said wall portion and directed inwardly toward the flange of the other wall portion; said flanges extending for more than half the length of said elongated side walls; a tubular ferrule surrounding the lower portion of said handle and said wall portions and extending downwardly below the lower edges of said wall portions; a bristle portion having its upper end telescoped within the lower end of said ferrule and disposed below the lower edges of said wall portions; solidified bonding compound disposed within said ferrule, bonding the upper end of said bristle portion into a solid bristle knot, and extending upwardly within said ferrule above said flanges thereby rigidly bonding and locking said wall portions to said bristle portion.

3. A brush structure comprising a hollow, thin-walled handle; said handle affording downwardly projecting elongated side walls and shorter end walls, said side walls providing parallel and laterally spaced wall portions at opposite sides of said handle; the lower edge portions of said wall portions being turned inwardly toward each other to form inwardly directed flanges; said flanges extending for more than half the length of said elongated side walls; a tubular ferrule surrounding the lower portion of said handle and said wall portions and extending downwardly below the lower edges of said wall portions; said inwardly turned lower edge portions of said wall portions being generally inwardly spaced from said ferrule; a bristle portion having its upper end telescoped within the lower end of said ferrule and disposed below the lower edges of said wall portions; solidified bonding compound disposed within said ferrule, bonding the upper end of said bristle portion into a solid bristle knot, and extending upwardly within said ferrule above and on either side of said flanges thereby rigidly bonding and locking said wall portions to said bristle portion.

4. A brush structure comprising a hollow, thin-walled handle; said handle affording downwardly projecting elongated side walls and shorter end walls, said side walls pro-

viding parallel and laterally spaced wall portions at opposite sides of said handle; a tubular ferrule surrounding the lower portion of said handle and said wall portions and extending downwardly below the lower edges of said wall portions; the outer surfaces of said wall portions tapering slightly downwardly and inwardly away from the inner surface of said ferrule and angling abruptly outwardly toward said ferrule adjacent to the lower edges of said wall portions to afford outwardly directed, elongated flanges; said flanges extending for more than half the length of said elongated side walls; a bristle portion having its upper end telescoped within the lower end of said ferrule and disposed below the lower edges of said wall portions; solidified bonding compound disposed within said ferrule, bonding the upper end of said bristle portion into a solid bristle knot, and extending upwardly within said ferrule above said flanges thereby rigidly bonding and locking said wall portions to said bristle portion.
